United States Patent Office

Des. 209,869
Patented Jan. 9, 1968

209,869

CONTAINER FOR MEMORY DISCS OR THE LIKE

Charles W. David, Marina Del Rey, Raymond Stuart-
Williams, Pacific Palisades, and Eugene A. Munson,
Torrance, Calif., assignors, by mesne assignments, to MRX Corporation, Hawthorne Calif., a corporation of California

Filed Aug. 8, 1966, Ser. No. 3,389

Term of patent 14 years

(CL. D58—17)

FIG. 1 is a perspective view of a container for memory discs or the like embodying our new design;

FIG. 2 is a front elevational view thereof; and

FIG. 3 is a bottom plan view thereof.

We claim:

The ornamental design for a container for memory discs or the like, substantially as shown.
